VACUUM CLEANER HOSE HANDLE OR SIMILAR ARTICLE

John H. Bowers, Jr., Greenwich, John J. Kowalewski,
Riverside, and John J. Moughty, Old Greenwich, Conn.,
assignors to Electrolux Corporation, Old Greenwich,
Conn., a corporation of Delaware

Filed Dec. 6, 1966, Ser. No. 4,939

Term of patent 14 years

(Cl. D9—2)

FIG. 1 is a side elevational view of a vacuum cleaner hose handle or similar article showing our new design;

FIG. 2 is a top plan view thereof;

FIG. 3 is a bottom plan view thereof;

FIG. 4 is a view thereof looking at the right end as shown in FIG. 1; and

FIG. 5 is an end view thereof looking at the left end as shown in FIG. 1.

The broken lines shown in FIGS. 1, 2 and 3 are for illustrative purposes only.

We claim:

The ornamental design for a vacuum cleaner hose handle or similar article, as shown and described.
